UNITED STATES PATENT OFFICE.

GEORGE BENNETT BOWELL, OF WEST KENSINGTON PARK, ENGLAND,
ASSIGNOR TO THE PEARSON FIRE ALARM SYSTEM, LIMITED, OF
LONDON, ENGLAND.

AUTOMATIC FIRE-ALARM TRANSMISSION.

SPECIFICATION forming part of Letters Patent No. 777,067, dated December 13, 1904.

Application filed July 7, 1902. Serial No. 114,646. (No model.)

To all whom it may concern:

Be it known that I, GEORGE BENNETT BOWELL, a subject of the King of Great Britain and Ireland, residing at 70 Sinclair road, West 5 Kensington Park, in the county of London, England, have invented certain new and useful Improvements in Automatic Fire-Alarm Transmission; and I do hereby declare the following to be a full, clear, and exact description 10 of the invention, such as will enable others skilled in the art to which it appertains to make and use the same.

The object of this invention is to provide automatically by a single party-wire connecting 15 a number of buildings with one central office a means, first, for immediate communication of a fire-call from any such building in case of excessive heat acting upon any thermostat installed in that building; secondly, means 20 for immediate communication of a call distinct from a fire-call in case of a connection in a building failing; thirdly, means for immediate communication from a building in case of a battery failing at that building, and, 25 fourthly, means for disconnecting any battery which fails at a building and connecting the local circuits of such buildings to the main line in such a manner as to enable a temporary supply of current to be furnished from the main 30 line to continue the work normally performed by the local battery.

For the sake of clearness I will describe this present invention in its simplest form; but in doing so I do not bind myself to any particular 35 form of apparatus in detail.

From the central office a single series circuit is provided which calls at each installation, this line being maintained normally as a constant-current circuit from a battery at the 40 central office. Upon an interruption of this main line recording instruments in the office are made to operate in the usual manner. At each automatic transmitting-station I provide in series with this main line a code break- 45 wheel, an electromagnet, and a switch. The code-break is driven when released by the electromagnet by a train of clockwork in the usual manner, and a detent is provided, so

that during the rotation of the break-wheel the clockwork cannot become locked. These 50 are the parts connected to the main-line circuit. The local circuit, which consists, usually, of a duplicate pair of wires throughout the building, each one having in series with it a number of thermostats or fuses, which 55 would serve to cut out their circuits when acted upon by heat, is provided with a battery, preferably of a type adapted for closed-circuit working, and a relay, the contact of this relay being connected in shunt with the coils of the 60 electromagnet in the main-line circuit and normally keeping them out of action. The switch in the main-line circuit is operated by the train of clockwork when the break-wheel has been released, either by a fire-alarm, by a disconnection on the building's wires, or by the 65 exhaustion of the local battery, and when this switch is operated it cuts out the local battery and cuts into the main line for a supply of current to keep the installation working until the local battery has been attended to. However, should the starting of the 70 clockwork-train have been caused by a break in a building-wire if the two building-loops are in series another contact device driven by 75 the clockwork bridges first the one loop and then the other, so that if the break is on one loop only the transmitter's break-wheel will only complete its first round; but should both loops be cut out the transmitter continues to 80 turn in its call. If desirable, a local bell may be added at any or all of the installations and connected to be rung off the local battery by means of a back contact on the local-circuit 85 relay.

In the accompanying sheet of illustrative drawings, Figure 1 is a diagram showing the instrument and different circuits for one installation, several such installations being connected to a single party-line connecting a number of buildings to be protected to one central office; and Fig. 2 is a similar diagram showing a slight modification by which a trouble or primary call is also given when a fault occurs in the local circuit. Fig. 3 is a plan 90 of a transmitter constructed according to this 95

invention, showing the mechanism run down after having given a fire-call. Fig. 4 is a section taken through the transmitter break-wheel.

5 The break-wheel *a* is mounted on the axle *b* and is driven by clockwork to make one revolution. It carries on its periphery the insulating-pieces *c*, that determine the signals transmitted. The brush *t* bears on the break-wheel. The wheel is also provided with an insulated metal segment 27, that makes contact with a second brush 28 at the same time that the brush *t* is raised off the break-wheel. The detent *d* is mounted on the pivot *f*, and 15 one arm is operated by the cam *g* in such manner that in the position shown the other arm holds up the armature *h* of the electromagnet *E*.

To put the parts of the transmitter in their 20 normal working condition, the shaft *b* is rotated or wound up clockwise against the resistance of a spring until the pin 5' comes in contact with the other side of the arm *n*. The cam *g* in this position will have released in 25 its backward motion the detent *d*, the part in contact with and the projection *i* being raised out of the way by the projection of the cam. Normally a projection *i* on the armature *h* prevents the arm *l* of the escapement 30 of the driving clockwork from vibrating, and consequently the break-wheel from rotating; but when the armature is attracted or held up the arm is free and the wheel rotates until stopped, as hereinafter described, or until it 35 has completed its one revolution. An eccentric *m* actuates through the rod *n* the block *o*, carrying contact-strips arranged between two sets of contact-springs with which they make contact.

40 *e* is a relay-magnet whose armature when attracted makes an electric contact at *p*.

The transmitter *T* in the single party-circuit 1 2 is driven by clockwork and can make a complete revolution giving two rounds when 45 released. The transmitter *T* is released when the electromagnet *E* is cut into the main circuit 1 2. The electromagnet *E* is connected into the main circuit, but is short-circuited by the switch *S* when held in the position 50 shown by the magnet *e*, arranged in the local circuit, so that if the local circuit is broken the transmitter is released. The local circuit consists of the two parallel wires 3 4, having inserted the fuses *f* and connected to the terminals 5 6 and 7 8, respectively. The contacts 11 and 16, also 12 and 17, and also 13 and 18 are connected together. The contact-bars 19, 20, 21, and 22 are operated together by the cam *m* on the transmitter at the end 55 of the first round. The main-line circuit is 1, S, 11, 21, 12, T, 2. The local circuit is B, 5, 3, 6

9, 7, 4, 8, *e*, 13, 22, 14, 10, B. If a fault occurs in either of the wires 3 or 4, the current

will still pass through the other and hold the 65 switch *S*.

The wires 3 4 can be separately tested by breaking the contact at 23, 24, 25, or 26. If, however, the battery fail or the fuses in the double wires 3 4 are burned, the magnet *e* loosens 70 the switch *S*. The current from the main line then passes through the magnet *E*, as follows: 1, E, 11, 21, 12, T, 2. When the magnet *E* is cut into circuit, the armature *h* is attracted to the position shown, and immediately the transmitter begins to rotate, and when the strips *c* are passing by the brushes the arm is held up, the detent *d* being in the position shown. Normally the armature *h* is down, preventing the arm *l* from vibrating and bearing on the 80 reduced part of the cam. The armature *h* cannot thus be released by the breaking of the circuit in giving the signal. The magnet *E* releases the transmitter and it makes its first round, (half a revolution,) giving its signal 85 at the central office. At the end of the first round the cam *m* causes the contact-bars 21 22 to break their connection and the contact-bars 19 and 20 to make their connection. The current from the main line then passes as 90

5, 3, 6,

follows: 1, E, 16, 19, 15, 7, 4, 8, *e*, 18, 20, 17, T, 2. The resistance *R* is a shunt between 16 and 17 and takes a portion of the main current. The magnet *e*, if the wire 3 or 4 is intact, now attracts the switch *S*, and the magnet *E* is short-circuited and the transmitter *T* is again held up, the arm *h* being released both from the attraction of the magnet and the detent *d*. The attendant at the central 100 station having thus only received the single signal is notified that the local battery of this installation is spent. If, however, the fuses in the wires 3 4 are burned, the whole current passes through the resistance *R*, the switch *S* 105 is not operated, the magnet *E* is not short-circuited and still holds up the armature *h*, and the transmitter *T* makes its second round, giving the second or fire call at the central 110 station.

In the modification shown in Fig. 2 the transmitter *T* is provided with an insulated piece 27, mounted on the transmitter-wheel, and at the half-revolution or first round of the transmitter making contact with the brush 28, 115 and also makes contact with the transmitter-brush and raises it off the break-wheel.

The different constructions are similar to those already described, the contact alone being slightly different. In the normal position the main-line circuit is 1, S, T, 2. The local circuit is B, 29, 30, 31, 32, 3, 33, 34, 35, 36, 37, 4, 38, *e*, B. If the local circuit is broken from any cause, the magnet *e* releases the switch *S*, and the main circuit is then through the magnet *E*, which releases the transmitter. At the end of the first round the piece 27 120 makes contact with the brush 28 and the con-

125

tact-bars 30 35 break their contacts, and the contact-bars 39 40 make their contacts. Then the main circuit is as follows:

5	1	41, 40, 42, R	28, 2.
		32, 3, 33, 39	38, e
		37	4

The magnet *e* then attracts the switch *S* and short-circuits the magnet *E*, so that the transmitter is arrested, provided that either the wire 3 or 4 is intact. A single round signal is thus received at the central station, and the attendant is thus notified that either the battery has failed or that there is a break in one of the wires 3 4. If, however, the wires 3 4 are both broken, the whole current passes by 1, 41, 40, 42, R, 28, 2, and the transmitter makes its second round or fire-call.

In order to insure that the transmitter shall not be stopped owing to the momentary breaking of the main circuit when the brush is passing over the usual insulating - pieces in the transmitter-wheel, the detent *d*, operated by the cam *g* on the transmitter-wheel, holds up 25 the armature of the magnet *E* while the brushes are passing over the code portion of the wheel.

What I claim, and desire to secure by Letters Patent, is—

30 1. In a fire-alarm installation the combination of a constant-current main circuit, a local circuit, a transmitter in the main circuit that when released interrupts the main circuit, a transmitter-controlling magnet in the main circuit, a switch in the main circuit, an electromagnet in the local circuit that operates the main switch to shunt the main-circuit magnet when the local circuit is broken, and a local switch operated by the transmitter and

adapted to place the local circuit in the main circuit.

2. In a fire-alarm installation the combination of a constant-current main circuit, a local circuit, a transmitter in the main circuit that when released interrupts the main circuit, a transmitter-controlling magnet in the main circuit, a switch in the main circuit, an electromagnet in the local circuit that operates the main switch to shunt the main-circuit magnet when the local circuit is broken, a local switch operated by the transmitter and adapted to place the local circuit in the main circuit, a detent, and a detent-cam on the transmitter that operates the detent when the transmitter is interrupting the main circuit so as to hold the transmitter unlocked.

3. In a fire-alarm installation, a transmitter consisting of a code break-wheel escapement - clockwork driving the code - wheel, brushes bearing on the code-wheel, a magnet, a magnet-armature that when released locks the escapement, and an eccentric on the break-wheel, an eccentric-strap, and a switch operated by the eccentric-strap.

4. In a fire-alarm installation, a transmitter consisting of a code break-wheel escapement - clockwork driving the code - wheel, brushes bearing on the code-wheel, a magnet, a magnet-armature that when released locks the escapement, a cam on the break-wheel, a detent operated by the cam and adapted to hold the armature in its attracted position.

In testimony whereof I have affixed my signature in presence of two witnesses.

GEORGE BENNETT BOWELL.
